UNITED STATES PATENT OFFICE.

EDMUND W. WOODRUFF, OF WASHINGTON, DISTRICT OF COLUMBIA.

FILE OR DOCUMENT HOLDER.

SPECIFICATION forming part of Letters Patent No. 415,429, dated November 19, 1889.

Application filed September 17, 1889. Serial No. 324,171. (No model.)

To all whom it may concern:

Be it known that I, EDMUND W. WOODRUFF, a citizen of the United States, residing at Washington, in the District of Columbia, 5 have invented certain new and useful Improvements in File or Document Holders; and I do declare the following to be a full, clear, and exact description of the invention, such as will enable others skilled in the art to 10 which it appertains to make and use the same.

My present invention relates to that class of document or file holders in which the box is formed by a bottom, a front at right angles thereto, and two side pieces, between 15 which and toward the front or bottom a file-board or follower is situated and adapted to be adjusted.

My invention relates more particularly, 20 first, to means of an improved character by which the file-board is held in place in an upright position to compress and hold the contents of the file-box, or is permitted to fall into an inclined position to release said contents and allow of their convenient examination; second, to improved devices whereby a 25 file box or holder may be suspended upon the front of its cabinet at the entrance of its pigeon-hole or space.

The invention consists in the parts and combinations thereof, or in their equivalents, hereinafter particularly described and claimed.

In order to make my invention more clearly understood, I have shown in the accompanying drawings means for carrying the same into practical effect.

In said drawings, Figure 1 is a vertical section of a portion of a cabinet and file-holder embodying my invention. Fig. 2 is a similar 40 view of a holder suspended and with the file-board in an inclined position, ready for the inspection or removal of the contents. Fig. 3 is a transverse section, looking toward the back of the file-board. Fig. 4 is a perspective view of a file-board having a somewhat different form of clamping device, also embodying my invention. Fig. 5 is a perspective view of a portion of the cabinet and box, illustrating the means for suspending the 45 latter.

Referring to the drawings, A indicates a portion of a case or cabinet, of which a a' are

two shelves, a being the upper and a' the lower relative to the file-box, which is shown in connection with them.

B is the file-box, of which the front b is of 55 such height as to neatly fill the space between shelves a a'. The box here shown is of the type known as "horizontal," in which the file-board operates toward and from the bottom and the papers or files lie in horizontal planes when the box is in place upon its shelf; but certain of my improvements herein described are applicable to holders in which the follower operates toward and from the 60 front, and in which the files are always upright, and I claim such invention whether used with a horizontal or with an upright file-holder.

I will first describe the means whereby the 70 holder or box is suspended upon the front of the cabinet.

C is a tongue, which is pivotally mounted upon the forward end of a slide D by means of a pin c. The slide is mounted upon and 75 is movable toward and from the front edge of the shelf a', being guided and held upon the shelf by means suitable to permit this movement—such, for instance, as headed screws d, passing through a longitudinal slot d' in the 80 slide and securely fixed in the shelf. In such case the slot d' is properly countersunk or rabbeted, as shown, Fig. 5, so as to bring the tops of the screw-heads flush with or below the surface of slide D. A stop is provided 85 which prevents the forward oscillation of the tongue C beyond the desired angle—such, for instance, as a projection c', adapted to abut against the front end of the slide. A groove e in the bottom E of the box is adapted to receive the parts C and D when the former is 90 folded down upon the slide and the box is upon the shelf a', thus permitting the box to slide into its place or to be drawn out from the cabinet.

F is a plate or metal strap secured in or 95 across the groove e, so as to leave an aperture adapted to receive the tongue C. This plate is situated at such distance from the front of the box that it will reach and be engaged by said tongue just before the box is 100 sufficiently drawn out to admit of its being tipped forward and downward to its suspended position, thus insuring that the file-

box shall not be hastily and partially drawn forth and allowed to tip without engaging the tongue, which would ordinarily result in the falling of the box to the floor.

5 In order to prevent the box from being tipped until it has been drawn forward into engagement with the tongue, as above described, the sides b' are made of such shape (say rectangular) and length that their ends 10 shall be flush with the top of front b , and shall extend back therefrom in engagement with the under side of shelf a , as shown at b^2 , when the holder is in place in the cabinet.

The tongue C is provided with a shoulder 15 c' , which limits the distance to which the tongue shall pass into or beneath the plate F , and which serves to support the weight of the box when suspended. This shoulder c' also forms an offset, which holds the end of 20 the tongue, when folded, at a sufficient distance above the plate D to permit plate F to pass beneath the tongue as the file-box is drawn forward.

I will now proceed to describe my improved 25 means for clamping the file-board and for holding it in an inclined position. It is desirable that the file-board tip from the bottom—that is to say, upon an axis substantially coincident with the bottom edge of the board—30 as such movement better exposes the contents of the box to view, and does so without making it necessary to slide the file-board toward the open end of the file-box. It is also desirable that when in clamping the file-board its bottom edge shall have been brought 35 against the papers the operation of the clamping device shall not throw said bottom edge farther forward. When this latter action occurs, the clamp offers much resistance, considerable force is necessary to close it, and the parts are frequently bent, broken, or loosened 40 from the file-board. By my improvement these various difficulties are overcome, and a clamping device is produced which, while it holds the contents of the file-box firmly and 45 with all the desired pressure, can be operated by a mere touch.

Referring to that embodiment of my invention which is illustrated in the accompanying drawings, it will be seen that the clamp 50 consists of a system of two levers and a link, the first G being substantially horizontal, pivoted to or beneath the bottom edge of the file-board, as at g , extending backward (toward the open end of the file-box) therefrom, and adapted at its outer end g^2 to bear downward upon the bottom (or front) of the file-box, which is provided with the usual undercut clamping-groove b^3 . The second lever H 55 is pivoted at h to the lever G , such pivotal point being situated at the outer side of pivot g , and at its upper end forms or is provided with an operating-handle h' . At a point intermediate between said handle and pivot h 60 the lever H is hinged by a pin h^2 to the lower end of a third bar I , which latter at its upper end is pivoted in or on the file-board by pivot i .

J indicates a cross-head or two lateral projections, which are adapted to engage the under side of the undercut clamp-groove b^3 , 70 and obtain, in conjunction with the outer end of lever G , a secure grip upon the file-box and hold the file-board rigidly in the desired position. The projections J may be formed with or attached to the file-board, as shown 75 in Figs. 1, 2, and 3, or may be carried by the horizontal lever G at a point between the end g^2 , which bears upon the file-box, and the pivot g , as seen in Fig. 4.

In operating this clamping device to release the file-board from the position shown in Fig. 1, it is simply necessary to touch the inner side of the handle h' and give it a slight outward pressure. The pivots h , h^2 , and i being almost in a straight line, a very 85 light pressure will suffice to carry the pivot h^2 beyond (to the right in Fig. 1) the straight line drawn from pivot h to pivot i , whereupon the pressure of the papers will cause the file-board to fly open and into its inclined position, (shown in Fig. 2,) when the contents of the file-box will be ready for inspection. To close the file-board against the papers it is simply necessary to take the handle h' with the thumb and finger, press the lever H longitudinally till the file-board is at its lower edge in close contact with the papers, and then tilt the lever toward the file-board. Such action brings pivots h , h^2 , and i into a straight line, and finally carries pivot h^2 slightly past 100 such line, at which instant the handle h' comes in contact with the back of bar I , (or said bar is stopped by the meeting of its lower end with the file-board,) and the file-board is locked against movement forward or backward until released, as already described. The parts will be so proportioned that when locked as above set forth the file-board will be substantially parallel with the papers and at right angles with that part of the box in 110 which the clamp-groove b^3 is formed. The projections J , when carried by the follower or file-board, are preferably formed upon the lower end of a metallic plate K , riveted to the file-board. Such plate also forms a convenient bearing for the pivot g . As the clamping strain of the toggles H and I tends to force plate K in a direction parallel with the follower-board, and as the latter is frequently 115 made of soft wood, I provide said plate with an inward projection k , adapted to fit tightly in a corresponding recess bored in the file-board. This projection, being of considerable diameter, gives much more security than the ordinary rivets against loosening by 120 pressure in lines parallel with the file-board. Bearings for pivots i are also preferably furnished by a plate L , having ears l , and a projection l' analogous to that of the plate K . Plate L is also securely riveted to the file-board, and 125 by virtue of its projection l' is adapted to resist the upward pressure brought to bear upon it by the operation of the toggles.

Additional stability is given to the file-

board by a projection a^4 formed upon the outer end of lever G, and adapted to fit between the sides of the clamp-groove b^3 . The board is thus prevented from being accidentally twisted out of its proper position, the projection a^4 acting as a guide whether the file-board be vertical or inclined.

Having thus described my invention, what I claim is—

- 10 1. In a file or document holder, the combination, with a file-box and a follower or file-board therefor, of a lever pivotally connected at one end with said follower, extending rearwardly therefrom and adapted at its free end to bear against the file-box, projections which engage the file-box oppositely to said lever, and toggles connected with said follower and with said lever for oscillating the latter upon its pivot toward or from the file-box to engage
- 15 20 the latter or be disengaged therefrom and clamp or release the follower, substantially as set forth.
- 20 2. In a file or document holder, the combination, with the file-box having a clamp-groove and the follower-board, of a plate secured to said board and provided with projections adapted to engage said clamp-groove, an outwardly-extending lever pivoted to said plate and adapted to bear at its free end upon
- 25 30 the file-box, and toggles adapted to oscillate said lever toward or from the file-box, substantially as set forth.
- 30 35 3. The combination, with the file-box having a clamp-groove and the file-board, of a lever pivoted to the latter and having a guiding projection a^4 , toggles for depressing said lever, and projections connected with the file-board for engaging the under side of said clamp-groove, substantially as set forth.
- 35 40 4c 4. The combination, with the file-board and levers for clamping the same, of a plate secured to said file-board forming a pivotal bearing and provided with an enlargement or projection seated in the file-board for resisting pressure parallel with the board.
- 40 45 5. The combination, with the cabinet or

shelf, of a file box or holder, a slide mounted on said shelf, a tongue pivoted upon said slide and adapted to fold toward the same or to stand upward therefrom, and means carried by the said holder whereby the latter is engaged and held by said tongue, substantially as set forth.

6. The combination, with the shelves, of a slide mounted upon the lower shelf, a tongue pivoted and adapted to fold upon the slide, and a file-box provided with means for the engagement of said tongue, the file-box having side pieces, the ends of which extend from the top of the front of the box in a direction parallel with its bottom, and which are adapted to engage the bottom of the upper shelf to prevent the premature tilting of the file-box, substantially as and for the purpose set forth.

7. The combination, with a shelf or support, of a file box or holder, a slide mounted on said shelf, a tongue pivoted upon said slide and adapted to fold toward the same or to stand upward therefrom, said tongue and slide having a shoulder offset or support adapted to cause a space to be left between said two parts, and means carried by said holder whereby the latter is engaged and held by said tongue, substantially as set forth.

8. The combination, with a shelf or support, of a file box or holder, a slide mounted on said support, a tongue pivoted upon said slide and adapted to fold toward the same or to stand upward therefrom, said tongue and slide being provided with a stop to limit the forward oscillation of the former, and means carried by said holder whereby the latter is engaged and held by the tongue, substantially as set forth.

In testimony whereof I affix my signature in the presence of two witnesses.

EDMUND W. WOODRUFF.
